UNITED STATES PATENT OFFICE.

ROBERT ARTHUR WILLIAMS, OF LLANWNDA, NEAR CARNARVON, WALES.

TWO-STROKE INTERNAL-COMBUSTION ENGINE.

1,354,931.

Specification of Letters Patent.

Patented Oct. 5, 1920.

Application filed February 1, 1918. Serial No. 214,938.

To all whom it may concern:

Be it known that I, ROBERT ARTHUR WILLIAMS, a subject of the King of Great Britain and Ireland, and a resident of Porthyr-Aur, Llanwnda, near Carnarvon, North Wales, have invented new and useful Improvements in and Relating to Two-Stroke Internal-Combustion Engines, of which the following is the specification.

- 10 This invention relates to improvements in two-stroke internal combustion engines having as their object to provide better means than have hitherto been employed in engines of this type for delivery of air supply under initial compression in order to scavenge the working cylinder of its waste gases before delivery thereto of the new charge or air mixed with liquid fuel so as to insure that there shall be no waste of fuel by the passage of same through the exhaust port before compression. A further object of the invention is to provide better means for supplying and mixing the liquid fuel with the air for combustion just 25 prior to its delivery to the working cylinder.

I provide a delivery pipe or channel from the air compressor or pump formed in such manner and of such area at the junction of the said transfer pipe with the cylinder wall, that it embraces two separate ports or passages opening into the cylinder. The one of smaller area is first opened or uncovered by the piston in its working 35 or outstroke. Through this port air alone is first delivered to the working cylinder to scavenge same. The separate passage supplying air only extends for some distance into the said transfer passage or pipe so as 40 to insure that no fuel is delivered by the said port first uncovered by the piston. The air may be pumped and delivered in the usual manner by the opposite side of the working piston and the crank chamber, 45 or by a separate cylinder and piston connected to the same crank shaft as the working cylinder or by a separate rotary pump.

I provide arranged centrally within that division of the transfer passage forming a 50 continuation of the second port uncovered by the piston, a nozzle or jet for the delivery of liquid fuel under pressure, the jet being arranged also centrally within said passage. I provide a closed tank for the liquid fuel which may be fed by any suitable means from a main tank with a float

feed of the usual kind, but with a non-return valve between the two tanks. I provide a pipe connection from the said air delivery channel to the top of the liquid fuel supply tank, so that the air pressure and varying pressures within the said channel are transmitted to the surface of the liquid within same in order to deliver the liquid to the said jet or nozzle. I provide a needle 60 valve fitting the orifice of the said jet, the spindle of which passes through a gland on the wall of the said channel to the outside of the said wall, and is fitted with a knurled head handle for turning same. 70

The pressure transmitted to the surface of the liquid fuel in the tank by the described means causes a jet of liquid fuel to be delivered mixed with air to the working cylinder following each compression 75 stroke of the pump.

In a double acting two stroke engine having the exhaust port or ports and mixture or new charge port or ports placed midway in the cylinder, I provide one mixture or 80 the like delivery port and two scavenging air supply ports one on each side of the central mixture port, the three ports being arranged longitudinally in the cylinder wall.

And in order that my invention may be 85 completely understood reference should be made to the accompanying sheets of drawings which illustrate the preferred mode of carrying the invention into effect. It will be understood that the drawings are to 90 a large extent diagrammatic.

Figure 1 is an elevation, part section, of a double acting two stroke engine having an air compressor mounted on the same crank chamber.

Fig. 2 is a sectional elevation through the working cylinder.

Fig. 3 is a sectional plan through the center of the working cylinder and through the air compressor.

Fig. 4 is a diagram to show more clearly the method of working and the operation of the fuel feed.

Fig. 5 is a view of the inlet port to the working cylinder as it would appear from 105 the interior thereof.

In Figs. 1, 2 and 3, the air supply in the double acting two stroke internal combustion engine shown is provided by the air pump or compressor, the piston of which is 110 connected to the same crank shaft as that of the working cylinder.

A is the double acting working cylinder having the piston B therein adapted to have an explosion take place on each side of it, and provided with deflectors or baffle plates 5 C, C¹, on the one side, and similar deflectors or baffle plates C² C³ on the other side. D is the inlet port for the delivery of mixture, the one inlet port serving in this construction to supply the working charge 10 to both sides of the double acting piston. The air compressor cylinder E of usual construction is also double acting, it being provided with suction and delivery valves of usual construction on both sides of the 15 working piston E¹ therein for this purpose. The compressed air supply is delivered by the pipe F, see the diagram Fig. 4, and the sectional plan, Fig. 3, both ends of the compressor delivering to the one pipe F. The 20 air supply and pressure are controlled by any suitable valve fitted within the pipe F between the compressor and the working cylinder, a throttle valve G of the ordinary pattern being shown for this purpose in 25 Fig. 4. The piston B in approaching the end of its stroke at either end first uncovers the scavenging air port H or H¹, the port H being provided for the upper end of the working cylinder, and the port H¹ for 30 the lower end. The exhaust port I which is common to both working ends of the cylinder begins to open by the movement of the working piston simultaneously with the opening of the scavenging air port H¹ with 35 the piston in the position shown in Fig. 4, in order to displace and eject a portion of the exhaust gases from the combustion chamber at the lower end of the cylinder through the exhaust port I before the mixture or new charge port D is uncovered. The continued movement of the piston toward the end of the stroke uncovers this 40 delivery port D and mixture or new charge is delivered to the working cylinder simultaneously with the scavenging air from the scavenging air port until the piston reaches the end of the stroke as shown in Fig. 4. A similar operation takes place when the piston B approaches the end of the stroke 45 at the lower end of the cylinder, but the scavenging air port H first comes into operation, the mixture or new charge port D then serves to supply the upper end of the working cylinder, and the same series of 50 operations take place as in the lower end. The center of the port D is midway in the stroke of the piston B. K is the petrol or other liquid fuel supply tank which as shown in the diagram, Fig. 4, is connected 55 by the pipe K¹ to the compressed air supply channel F. By this means the air pressure in the supply channel F is conveyed to the surface of the liquid fuel in the tank K. The air pressure in the channel F varies, being at a maximum when the 60 65

pressor piston E¹ is at the end of its stroke. In Fig. 1, the pump or compressor piston E¹ is at the lower end of its stroke, while the working piston B is at its upper end. As the pump piston approaches the end of 70 its stroke, the air pressure conveyed by the pipe K¹ and transmitted to the surface of the petrol or the like tank K, forces the liquid fuel by the pipe K² connected at the bottom of the tank K to the pipe K³ and the 75 jet or nozzle K⁴, this jet or nozzle being fitted centrally within the pipe K⁵ which pipe is securely fixed within the port D opening into the cylinder wall. The nozzle K⁴ is provided with the adjustable screw-down needle valve L having the knurled head L¹ at its outer end. The thread on the end of the needle L fits a screwed cover L² closing a packing gland L³. By this means 80 therefore, a spray of liquid fuel is delivered through the port D directly the working piston B uncovers this port, this position of the working piston coinciding with the maximum air pressure on the surface of the liquid in the tank K. This pressure and 85 therefore the quantity of liquid fuel delivered by the nozzle K⁴ may be controlled by the throttle valve G, which valve may be placed at any suitable position in the air delivery pipe F and may be of any suitable 90 construction. Additional control of the supply of liquid fuel as also of scavenging air may be provided by the throttle valve M placed in the exhaust pipe I¹. The tank K is connected to the main supply tank (not 100 shown) of liquid fuel by the pipe O which pipe is provided with the small nonreturn valve O¹ that permits liquid fuel to flow into the tank K by the suction of the pump or by gravity, but prevents the passage of 105 either air or liquid fuel from the tank K to the pipe O, and therefore prevents the escape of air or fuel from the tank K to the main supply tank (not shown).

It will be observed that by this construction, the supply of liquid fuel is provided only at the time it is required, namely, at the opening or uncovering of the port J by the working piston and that the control provided by the throttle valve G or by the 115 valve M necessarily provides control simultaneously of the air supply for scavenging purposes, the air supply for combustion, and also of the feed of the liquid fuel, this latter supply being dependent upon and controlled 120 by the air pressure in the pipe F.

Further in the construction shown as applied to a double acting engine the arrangement serves to supply and control the supply of fuel and air for both ends of the 125 double acting engine.

The screwed holes P and P¹ at the upper and lower ends of the cylinder respectively are for the sparking plugs for ignition of the charge.

As shown in Figs. 1 and 3, the exhaust pipe I¹ may be fitted surrounding a portion of the air delivery pipe F in order to heat same.

5 What I do claim as my invention and desire to secure by Letters Patent is:—

1. The combination of a two stroke internal combustion engine having two intake ports in the cylinder wall, one for scaveng-

10 ing air and the other for fuel, said ports being controlled by the piston and arranged so that the scavenging air port will be un-

15 covered by the piston in advance of the fuel port, an air compressor, and means for sup-

plying compressed air from said pump simultaneously to both of said ports, said means comprising a single pipe leading from the compressor and connected with both of said ports, a fuel feeding nozzle ad-

20 jacent the fuel feeding port, and means for supplying fuel under pressure to said nozzle.

2. The combination in a two stroke internal combustion engine having two intake ports in the cylinder wall, one for scaveng-

25 ing air and the other for fuel, said ports being arranged so that the scavenging air port will be opened to the cylinder in ad-

20 vance of the fuel port, an air compressor connected with both of said ports, a fuel

30 tank, a fuel jet associated with the fuel port, a conduit leading from the fuel tank to the jet, and means connecting the fuel tank with the compressor whereby air pressure is sup-

35 plied to the surface of the liquid in the fuel tank to feed the same to the nozzle.

3. The combination in a two stroke internal combustion engine having two intake ports in the cylinder wall, one for scaveng-

40 ing air and the other for fuel, said ports being arranged so that the scavenging air

port will be opened to the cylinder in ad-

45 vance of the fuel port, an air compressor connected with both of said ports, a fuel jet associated with the fuel port, a fuel supply

50 tank, means connecting the fuel tank with the compressor whereby air pressure is sup-

45 plied to the surface of the liquid in the fuel tank to feed the fuel to the nozzle, and means for varying the air pressure whereby the

55 liquid fuel supply is simultaneously varied and controlled.

4. The combination in a two stroke internal combustion engine having two intake ports in the cylinder wall, one of said ports

55 being a scavenging air port and the other for fuel, said ports being arranged to be opened one in advance of the other, an air compressor, a pipe leading from the dis-

60 charge end of the compressor and communi-

port, a fuel supply tank, a fuel nozzle associated with the fuel port, a pipe connecting said fuel nozzle with the lower part of the fuel tank, and a pipe connecting the upper portion of the tank with the air pipe, and means for varying the air pressure in the air pipe whereby the liquid fuel supply is simultaneously varied and controlled.

5. The combination in a two stroke internal combustion engine having two intake 70 ports in the cylinder wall, one of said ports being a scavenging air port and the other for fuel, said ports being arranged to be opened one in advance of the other, an air

75 compressor, a pipe leading from the discharge end of the compressor and communicating with both the scavenging air and fuel port, a fuel supply tank, a fuel nozzle as-

80 sociated with the fuel port, a pipe connect-

85 ing said fuel nozzle with the lower part of the fuel tank, and a pipe connecting the upper portion of the tank with the air pipe,

means for varying the air pressure in the air pipe whereby the liquid fuel supply is simultaneously varied and controlled, and a screw 85

or needle valve for regulating the size of the orifice of the fuel nozzle.

6. The combination in an internal com-

bustion engine, of means for supplying com-

pressed air to the engine, a fuel port, a fuel

90 nozzle associated with said port, a fuel tank, a fuel supply pipe connected with the fuel

95 tank, a non-return valve permitting the pas-

sage of fuel from the fuel supply pipe to the

fuel tank but preventing the passage of air

100 or liquid from the pressure tank into the

supply pipe, and means connecting the fuel

105 tank to the compressed air supply whereby

liquid fuel will be fed to the nozzle by air

110 pressure.

7. The combination in a two stroke internal combustion engine having a central fuel port common to both working ends of the cylinder, and a pair of scavenging air ports, the fuel port and air ports being con-

105 trolled by the piston, said air ports being arranged one on each side of the central fuel port longitudinally of the cylinder so that said scavenging ports deliver respec-

110 tively to opposite sides of the working pis-

ton, in advance of the fuel ports, an air

115 compressor, a single pipe connecting the de-

livery of the air compressor with all of said

ports, a nozzle associated with the central

fuel port, and means for supplying liquid

115 fuel to the nozzle.
